METHOD AND APPARATUS FOR COMPENSATING FOR GRINDING WHEEL WEAR

Edward C. Taylor, Hartford, Vt., assignor to Van Norman Company, Springfield, Mass., a corporation of Massachusetts

Application August 28, 1948, Serial No. 46,638

7 Claims. (Cl. 51—165)

1

For the internal grinding of bore diameters so small that they are not capable of receiving a grinding wheel and a gauging feeler simultaneously, and particularly for smaller sizes of external ball races the internal grooves of which are obviously not susceptible to plug gauging, it has been proposed in an application for patent filed by Roger S. Pyne on August 2, 1948, Serial No. 41,996, now patent No. 2,584,449, dated February 5, 1952, that the feeding motion of the cross slide be interrupted at a fixed point and that the correct position of the grinding surface of the wheel at the end of the grinding operation be obtained solely by presetting the wheel relative to the cross slide before grinding is commenced. It was there further proposed that, after the termination of each grinding cycle and the removal of the cross slide to a position where the wheel is free of the work, the grinding wheel spindle be shifted on the cross slide until its grinding surface makes contact with a feeler having an adjustable, but normally fixed, position on the cross slide. This feeler is set so as to allow for the estimated wear of the wheel during the next grinding cycle; so that, if this estimate is correct, the end of the next grinding cycle will find the cross slide at its fixed terminal position and the grinding wheel worn just enough to bring the work piece to the correct internal diameter.

For most grinding operations this is sufficiently accurate, particularly if work pieces are gauged at intervals and corrections made in the position of the feeler, since the wear of a grinding wheel is on the order of one thousandth of an inch per cycle (the grinding of a single work piece) and the variation in wear between successive cycles is obviously of an even lower order. Though the variation in wear between successive cycles might seem to be negligible, it can easily be shown that unequal wear of the wheel is a real factor for consideration. It is apparent that, even though the difference of wear between one cycle and the next is of very small magnitude, the difference between the wear of a grinding wheel per cycle may be by no means negligible when the comparison is made between a new wheel and the same wheel when worn to the point where it is to be discarded. This difference in wear per cycle may show up as a steady drift in the size of the finished work pieces, since the rate of wheel wear per cycle is quite different for large and small wheels. Still more important is the sudden change in wheel wear per cycle which occurs when a new grinding wheel is substituted for a worn one. Here we have not only the effect above

2

noted of the change in diameter of the wheel, in this case a sudden change from minimum to maximum diameter; but also a sudden change in the hardness of the wheel being used, since no two wheels are exactly the same.

It is one object of the invention to provide a gauging method and apparatus which will preset the wheel a distance from the ideal diameter of the work piece such that, if the wheel wears the same amount that it did on the preceding work piece, the work piece in process will be ground to the correct diameter. In the usual case of a succession of work pieces being ground by the same wheel this will keep the error (ignoring errors caused by parts of the machine other than the gauging mechanism) within the variation in wear of the wheel between successive grinding cycles. If a wheel is changed, the first piece ground will be corrected by the wear of the previous wheel, and so will give a wrong finished size to that piece; but after two grinding cycles the machine will automatically settle down to the grinding of work pieces of the correct diameter without any laborious setting-up operation on account of the newly introduced wheel. The incorrect finishing of one or two work pieces, which may be discarded or used with companion races by special selection, is substituted for a manual cut-and-try adjustment at a lower cost and generally with less defective pieces. Other objects will appear from the following description and claims.

The invention will now be described with reference to the accompanying drawings, in which

Fig. 1 is an elevation, looking from the work head, of an oscillating grinder having wheel supporting slides and gauging mechanism constructed in accordance with my invention;

Fig. 2 is a top plan view thereof;

Fig. 3 is a view similar to Fig. 1 but showing one gauge head raised;

Fig. 4 is a diagram illustrative of the gauging method;

Fig. 5 is a view similar to Fig. 3 but with both gauge heads raised to clear them from the work head, and with the cover of one of them broken away to show the internal construction;

Fig. 6 is a side view of the grinding wheel head;

Fig. 7 is a section, on an enlarged scale, of the slides carrying the grinding wheel spindle and the gauging heads;

Figs. 8 to 15 are detail views showing successive stages in the grinding and gauging operations;

Fig. 16 is a wiring diagram of the automatic control mechanism which controls the slides and gauges; and

Fig. 17 is a similar diagram of the control circuit for the feeding mechanism.

The basic principle upon which this invention is based is shown in Fig. 4 in simplified form. In a manner to be described the active surface of the grinding wheel 4 is advanced, while in a gauging position remote from the work, until it strikes a gauge or feeler 2 which in its active position is always on a base line 3. For descriptive purposes the base line may best be considered as in line with the active surface of the grinding wheel when the latter has just finished grinding a correctly dimensioned work piece, although as will be seen later this restriction is not essential. The feeler 2 then moves out of the way, feeler 4 then taking over the control. The latter feeler has up to this time moved simultaneously with and at the same rate as the wheel 4, and is at a distance from the rear side of the wheel equal to w_1 , the radial wear of the wheel which occurred during the preceding grinding cycle. (How it got in that position will appear later.) It is desired to locate the active side of the wheel this distance w_1 beyond the base line 3, so that assuming the wheel will wear this same amount w_1 during the next grinding cycle the work piece so ground will be of the exact diameter desired. To set the wheel in this position C it is apparent that, were the feeler 4 left behind at the line 5, a distance $2w_1$ would exist between it and the rear side of the wheel. To close this gap the feeler must advance $2w_1$ while the wheel advances a half of this. Advantage is taken of this relationship by mounting the wheel and feeler 4 on separate slides in such a manner that they may have either the simultaneous motion mentioned above or a two to one motion with the feeler moving twice as fast as the wheel. If now the wheel and feeler are advanced from B in this ratio, the feeler will just catch up with the wheel when the latter is in the position C. By stopping the advance of the wheel and feeler at the instant when contact between them is made the wheel is automatically advanced a distance beyond the base line equal to the wear which occurred during the grinding of the previous work piece.

It can now be shown how the feeler 4 measures the wear on the wheel. Starting with the parts in position C, it should be stated that feeler 4 is so mounted that it can be moved away from the wheel so that the latter may be freed for grinding, but will return to its original position at the start of a succeeding gauging operation. In position C the feeler 4 is in contact with the surface of the wheel just before the start of a grinding operation. Position D is the same except that the wheel has gone through a grinding cycle and has returned to gauging position with its axis in the same position as before. It is clear that the distance between feeler 4 and the rear side of the wheel is equal to the wear on the wheel. Correction for the next grinding cycle is done by moving the front or active side of the wheel in a first step to the base line and then in a second step moving it ahead of the base line an amount equal to the measured wheel wear. As has been stated above, this is very simply done by moving the wheel and feeler 4 together until the forward side of the wheel strikes the feeler 2, then moving feeler 2 out of the way, and finally moving feeler 4 and the wheel forward with a respective speed ratio of two to one until the feeler catches up with the wheel.

The structure of one form of machine by which

this operation can be performed will now be considered. The drawings show details of the wheel head only, since this carries all the gauging mechanism and no change is necessary in the rest of the mechanism, which may be constructed as shown and described in the patent to Van Norman et al. 2,149,409 issued March 7, 1939. The wheel head comprises a table 6 running in suitable ways (not shown) in the base of the machine so as to cause axial approach of the wheel and work. Ways 7 on the table support the main cross slide 8 which is driven by a feed screw 9 between fixed positions on the table 6 by any suitable mechanism not here material. The only absolute criterion is that the slide 8 should have an accurately fixed limiting position at the end of the grinding operation, for it is the stopping of the slide 8 in this invariant terminal position, and not a gauging operation, that ends the grinding. The function of the gauging mechanism to be described is to change the position of the wheel on the slide 8 so that when the slide 8 stops the surface of the worn wheel will be at the correct location to give the desired diameter to the work piece.

Mounted in ways 10 on slide 8 is a feeler slide 11 and in ways 12 on slide 11 is a slide 13 carrying the grinding wheel spindle 14. If desired, the slide 13 could be mounted in the same ways 10 as slide 11, the two slides then being separated longitudinally. A feed screw 15 is held against axial motion by a thrust block 16 secured to the slide 8, and is threaded into the internally threaded end 17 of a second feed screw 18 held against axial motion relative to slide 11 by a thrust block 19 fastened to the latter. A nut 20 fixed to slide 13 has the feed screw 18 threaded through it. The pitch of the threads on screw 18 and in nut 20 is one-half that on feed screw 15 and the internally threaded portion 17 of screw 18, and the two sets of threads are of opposite hand. A shaft 21 driven from a motor 22 in a housing 23 on slide 8 carries a worm 24 engaging a worm wheel 25 secured to feed screw 15. The motor is of a slow speed type, for the amount of movement to be given to the slides 11 and 13 is very small. A second motor 26 of similar type drives a worm 27 engaging a worm wheel 28 on feed screw 18. When feed screw 15 is rotated and feed screw 18 is not, the slides 11 and 13 will be moved together at the same rate. When feed screw 18 is rotated and feed screw 15 is held stationary (its motor 22 not being energized) the slides 11 and 13 will be moved simultaneously but with the latter slide moving at half the rate of the former, since it is by the action of its reverse handed and half pitch driving threads backed away from the slide 11 as the two slides 11 and 13 are drawn along together by the action of the screw and nut 15, 17. Any other mechanism for moving the two slides alternatively at the same rate or with the feeler slide moving forward with the spindle slide but at twice the speed of the latter could of course be substituted.

Slide 11 has a pivot 29 on which is mounted a rocker 30 carrying a gauge housing 31 enclosing the feeder 4. A link 32 pivoted to the end of the rocker remote from the housing is coupled to the armature 33 of a solenoid 34, which could be replaced by the piston of a hydraulic cylinder if desired. When the solenoid (or hydraulic cylinder) is activated, the housing 31 is elevated (Fig. 5) to bring it and its gauge free of the grinding wheel so as to leave the latter unobstructed for a

grinding operation. When the solenoid is de-energized the housing drops until an abutment 35 strikes an adjustable stop 36 on the slide 11, thus positioning the housing (Fig. 7) for a gauging operation on the wheel. Alternatively the 5 housing may be raised by a cam on the main frame as the table 6 moves towards the work, as in the application of Roger S. Pyne, Serial No. 41,996, filed August 2, 1948, now Patent No. 2,584,449, dated February 5, 1952.

The main cross slide 8 has a bracket 37 having a pivot 38 upon which an arm 39 is mounted which carries a gauge housing 40 for the feeler 2. A depending arm 41 is connected to a counter-balance spring 42 anchored to the bracket 37, and is coupled by a link 43 to the armature 44 of a solenoid 45 (or to the piston of a hydraulic cylinder) acting in this case to push rather than pull. Alternatively, as with housing 31, the housing 40 may be raised mechanically. In its elevated position (Fig. 3) the arm carries feeler 2 free of the wheel, and when lowered is positioned by contact between a stop 46 and the top of the bracket. A second stop 47 may if desired contact a dash pot plunger 48 to bring the arm to rest gradually, and a third stop 49 may contact a limit switch 50 which activates the gauging mechanism only when the arm is in lowered position. Other means for controlling the activation of the gauging mechanism are, however, preferred and will be described below. A corresponding counter-balance spring and dash pot may if desired be provided for the housing 31, but have been omitted from the drawing in the interest of clearness.

The construction of the two gauge housings and feelers are identical, except for a reversal of the direction of swing of the feelers, and will be described only in connection with the gauge housing 40. The housing is slidably mounted on the arm 41, and is provided with a micrometer adjusting screw 51 and a clamp 52 by which the housing may be secured in adjusted position. Pivoted at 53 within the housing is a gauge arm 54 having an upward extension 55 oscillatable between adjustable stops 56 and 57. When the arm is in the position of Fig. 5 the extension 55 is in contact with stop 56, and a spring contact 58 on the extension is in engagement with a screw contact 59 adjustable within the housing. The lower end of the gauge arm 54 carries a block 60 of hard material such as tungsten carbide, which is substantially unaffected by momentary contact with the rotating grinding wheel, and which forms the actual feeler determining the grinding wheel position. When in its presetting position remote from the work piece the wheel is advanced transversely of its axis by simultaneous movement of the slides 11 and 13 until it strikes the gauge block 60. This rocks the gauge arm 54 and breaks the contact between the members 58 and 59 and stops the motor 22 which is advancing the two slides. Preferably this activates an electromagnet 61 which holds the arm out of contact with the wheel until the magnet is de-energized by a subsequent closing of the limit switch 50 or by other means as will be described. The gauge in the housing 31 works in the same way except that contact between the wheel and the feeler (the feeler catching up to the wheel as described above) causes the breaking of the electrical circuit within the gauge, which stops the operation of motor 26 which operates the slides 11 and 13 in a two to one ratio.

One manner of automatically operating the machine to produce the desired pre-setting of 75

the grinding wheel is shown in Figs. 16 and 17. The control is accomplished by connecting commercial relays and switches, the construction of which is of no interest here, in such a manner that the sequence of operations described above will be performed automatically once the machine is set in operation. The operating coils and contactors of each relay are, in accordance with the convention, shown separate, which greatly simplifies the drawing, but the several parts of a single relay are indicated by a single symbol. Such symbols are keyed to the machine described above in accordance with the following plan. Limit switches are indicated by L followed by the number of the part which operates them, and then by F or R depending on whether they are operated on the forward or return stroke. Thus L8R would be a limit switch operating on motion of table 8 away from the work. Control relays are indicated by C and time delays by T, the number following this letter indicating the part controlled. A normally open contactor is shown by spaced lines, a normally closed one by spaced lines with a diagonal through them; and relay activating coils by a zig-zag line.

On depressing the starting button 62 a relay C6F in line 13 (having a contactor bridging the starting button to permit the latter to be released without opening the circuit) is activated, starting the motor (not shown) which drives the table 6 into operative position. The relay C6F also has a contactor of the self-holding type in a line 87 which contains the solenoids 34 and 45, so that as the table 6 starts to move towards the work the feeler housings will be raised out of the way. The motor is stopped by the limit switch L6F which opens the circuit through the coil of C6F when the table has reached the desired position. The limit switch has for this purpose a normally closed contact in line 63, but has as well a normally open contact in line 64 in series with normally closed contacts on a relay C8F and the activating coil of a relay C8 which controls the direct current variable feed mechanism for slide 8 shown in Fig. 17. The switch L6F also controls, through a branch line 65, a series of parallel lines 66, 67 and 68.

When C8 is activated current flows (Fig. 17) through the normally closed contacts 69 of relay C8A, through a high speed rheostat 70, and through the armature 71 of the motor which operates cross slide 8. The field 72 of this motor is connected across the line. The slide will move at a rapid traverse rate until limit switch L8A is closed, which closes the energizing coil of a fast-slow relay C8A, opening contact 69 and closing contact 73. Current then flows through the slow speed rheostat 74 and through the motor armature. The relay C8A has contacts 75 which are closed to bridge L8A, which is closed only momentarily. When limit switch L8F is closed by slide 8 reaching the predetermined position for termination of the grinding operation the relay C8F is activated, opening the normally closed contact in line 64 and deactivating relay C8 to stop the feed. Contacts on relay C8F also bridge L8F to preserve the relay in operation. It should be stated that the several limit switches controlling the motion of slide 8 are preferably mounted on the handwheel on feed screw 9 or a part similarly geared-up rather than directly on the slide itself, in order to magnify the motion and increase the accuracy of the terminal position of the slide when grinding ceases.

Operation of relay C8F also activates line 63

and starts the operation of a time delay relay T8F. When the contacts of this relay close, the line 76 is activated together with the relay C22R, which starts the motor 22 to back the wheel away from the work, the feeler 4, although elevated in inactive position, moving away also at the same rate. The delay caused by T8F is sufficient to permit the wheel and work to "spark out," an operation usually desired in accurate work. Closure of the T8F contacts starts a second time delay relay T22R which controls the duration of the backing away movement of the wheel and feeler slides. This backing away is sufficient to clear the wheel gradually from the work, in order to avoid marks; and also insures that the wheel 15 will be positioned in gauging position with no possibility of striking the gauge 2 even though the wheel may have worn less than the amount for which it was preset on the preceding cycle.

When T22R has run its timing cycle its contacts in a line 77 close, and current passes through a normally closed limit switch L6R and through a relay C6R which operates the motor (not shown) which drives table 6 in a direction to withdraw the wheel from the work. The relay 25 has contactors bridging those of T22R so as to maintain C6R in operative condition after the release of the former. As the table 6 moves back, L6F is released, resetting relays C8A and C8F, and opening the contacts of the latter which are 30 in line 68, 76 in series with C22R. Interruption of current flow through the latter stops the rearward motion of slides 11 and 13.

When the table 6 reaches its "out" or gauging position a limit switch L6R is activated, having contacts in line 77 which open to interrupt the current through C6R and stop the table. Contacts of L6R controlling both lines 78 and 79 are closed to activate a time delay relay T22F which has several functions. First it has normally 40 closed contacts in line 80 which when the limit switch L6R is closed activate a relay C8R which drives the motor of main cross slide 8 rearwardly, so that the wheel will be backed off sufficiently to allow for the amount of stock to be removed from the next work piece. It should be noted that the absolute position of the slides 11 and 13 (considering them together as a unit) during gauging by 45 2 is of no importance since the gauge 2 moves with the slide 8, and all that this gauging does is to reposition the wheel spindle with respect to the slide. If the slides 11 and 13 have been backed off an extra long distance, for example, they will simply have to be moved ahead a similar distance in the next operation until the wheel makes contact with the feeler 2.

When the time cycle of T22F expires C8R is de-energized, stopping the retraction of slide 8, and contacts of T22F in line 81 are closed, activating a relay C22F which controls the motor 22 which drives the slides 11 and 13 forwardly at the same rate towards gauge 2. When contact is made between the gauge 2 and the wheel the gauge 50 opens its contacts, activating an electronic relay 82 which in turn controls a relay C26F energizing the gauge-holding magnet in gauge 2 and simultaneously opening the circuit in line 81 to de-energize relay C22F and arrest the forward movement of the feeler and wheel slides.

The wheel is now in such a position on the main slide that if the cycle of the machine were performed without a work piece the active surface of the wheel would be just at the position of the surface of a correctly ground work piece when the main slide stopped. It is necessary, as 55

described above, to advance the wheel beyond this position on the main slide by the amount of wear suffered by the wheel during the grinding of the preceding work piece. The opening of the gauge 2, as stated above, causing activation of the relay C26F which opens the line 81 and stops the motor 22 which was causing the slides to move forwardly at the same rate. The relay C26F also closes the circuit through a line 83, containing a contactor of that relay, a relay 84 controlling the motor 26, and the normally closed contactor 85 of an electronic relay the coil of which is in series with the gauge 4. Motor 26 drives the shaft which moves slide 11 carrying the gauge 4 at twice the speed of the slide 13 carrying the grinding wheel spindle; and due to the considerations explained in detail above, the gauge 4 will contact the rear side of the wheel when the position of the wheel on the main slide 8 is correct. The opening of the gauge contact of 4 caused the electronic relay 85 to open the circuit through line 83, killing relay 84 and stopping the motor 26; and also opens line 86 to kill the relay C26F and energize the holding electromagnet of gauge 4. The cycle can now be resumed on another work piece, the opening of the L6R limit switch on subsequent movement of the table 6 causing resetting of the relays.

The gauging housings may be lowered by a cam on the frame, as mentioned above, or by de-energizing the electro-magnets which hold them. In the case shown activation of relay C6R opens a normally closed contactor in line 87 in series with the self-holding contactor C6F. As the normally closed contactor is opened the circuits through solenoids 34 and 45 will be opened and the feeler housings lowered into gauging position. The opening of the circuit also re-sets the self-holding contactor in its open position. In Fig. 3 housing 40 is shown elevated while housing 31 is in its lowered position. This showing is mainly for better illustration, and in the description above both housings have been described as raised and lowered together. It is in general unnecessary to lift housing 40 after gauge 2 has performed its function, for the gauge block of 2 is drawn away from the wheel by the activation of the holding magnet 61 a distance greater than the relatively small amount the wheel is later advanced by the forward movement of the slide 13. If it is desired to lift the housing 40 after its gauging function has been completed, however, its solenoid 34 may be controlled separately from solenoid 45 by the activation of relay C26F instead of by relay C6F, the control of solenoid 45 remaining with the latter relay.

What I claim is:

1. A grinding machine comprising a grinding wheel support, means for moving the support to a fixed terminal position on each grinding cycle, a grinding wheel rotatably mounted on the support, a first gauge having a fixed position on the support, a second gauge slidable on the support, means for moving the grinding wheel and the second gauge forwardly in unison until the forward side of the wheel contacts the first gauge, and means for then moving the second gauge and the wheel forwardly at a two to one ratio of speeds until the second gauge contacts the rear side of the wheel.

2. A grinding machine comprising a grinding wheel, a wheel spindle, a first slide carrying the spindle and movable transversely to the work, a second slide carrying the first slide and on which the first slide is movable transversely of

the work, a third slide carried by the second slide and movable relatively to the work in the same direction, means for moving the second slide to a fixed terminal position on each grinding cycle, a first gauge mounted in predetermined relation to said terminal position and positioned to be contacted by the front wheel surface, a second gauge carried by the third slide and positioned to make contact with the rear side of the wheel, and means for moving the first and third slides forwardly in unison until the front of the wheel makes contact with the first gauge and forwardly with a one to two ration of speeds until the second gauge makes contact with the rear of the wheel.

3. A grinding machine comprising a grinding wheel, a support therefor, a main cross slide, a spindle slide and a feeler slide superposed on the main slide and partaking in its movement, a first feeler carried by the main slide in position to engage the front side of the wheel, a second feeler carried by the feeler slide in position to engage the rear side of the wheel, means for moving the spindle slide and the feeler slide simultaneously at the same speed to bring the wheel into contact with the first feeler, and means to move the spindle slide and the feeler slide further in the same direction with the feeler slide moving twice as fast as the spindle slide to bring the feeler into contact with the rear side of the wheel.

4. A grinding machine comprising a grinding wheel, a spindle therefor, a main cross slide, a spindle slide and a feeler slide superposed on the main slide and partaking in its movement, a first feeler carried by the main slide in position to engage the front side of the wheel, a second feeler carried by the feeler slide in position to engage the rear side of the wheel, means for moving the spindle slide and the feeler slide simultaneously at the same speed to bring the wheel into contact with the first feeler, means to move the spindle slide and the feeler slide further in the same direction with the feeler slide moving twice as fast as the spindle slide to bring the feeler into contact with the rear side of the wheel, and means for interrupting said slide movements when the wheel contacts the respective feelers.

5. A grinding machine comprising a grinding wheel, a spindle therefor, a main cross slide, a spindle slide and a feeler slide superposed on the main slide and partaking in its movement, a first feeler carried by the main slide in position to engage the front side of the wheel, a second feeler carried by the feeler slide in position to engage the rear side of the wheel, means for moving the spindle slide and the feeler slide simultaneously at the same speed to bring the wheel into contact with the first feeler, means

50

60

to move the spindle slide and the feeler slide further in the same direction with the feeler slide moving twice as fast as the spindle slide to bring the feeler into contact with the rear side of the wheel, a prime mover coupled to said spindle and feeler slides for each of said movements, and means for stopping the movement of each prime mover when the wheel makes contact with the respective feeler.

6. A method of positioning, prior to the start of a grinding cycle, a grinding wheel on a feeding slide having a constant terminal position in said cycle, which comprises setting the active side of the grinding wheel tangent to a plane transverse to said slide and which will in said terminal position of the slide be tangent to a cylinder coaxial with the work piece and of a diameter equal to the finished diameter of a correctly ground work piece, determining on successive cycles the position of the diametrically opposite side of the grinding wheel when the active side is tangent to said plane, and prior to initiating the grinding cycle moving the active side of the grinding wheel beyond said plane a distance equal to one-half of the difference between successive positions of said opposite side of the wheel.

7. Mechanism for positioning a grinding wheel on a feeding slide prior to the start of a grinding cycle comprising a slide, a grinding wheel, a first gauge removably positioned to make contact with the active side of the rotating grinding wheel when said side is located on the slide tangent to a fixed plane transverse thereto, a second gauge positioned to make contact with the rotating grinding wheel at a point diametrically opposite the contact point of the first gauge, mechanism for advancing the grinding wheel and the second gauge simultaneously and at the same speed towards the first gauge, mechanism for advancing the grinding wheel and the second gauge simultaneously past the position initially occupied by the first gauge with the second gauge moving at a speed double that of the grinding wheel until the second gauge makes contact with the grinding wheel, and mechanism for moving said slide toward the work piece until said plane is tangent to a cylinder coaxial with the work piece and of a diameter equal to the finished diameter of a correctly ground work piece.

EDWARD C. TAYLOR.
